(57) **CLAIM**

The ornamental design for a coaxial cable connector, as shown and described.

DESCRIPTION

FIG. 1 is a front, top, left-side view of the coaxial cable connector;

FIG. 2 is a left-side elevational view thereof;

FIG. 3 is a right-side elevational view thereof;

FIG. 4 is a bottom plan view thereof;

FIG. 5 is a top plan view thereof;

FIG. 6 is a front elevational view thereof;

FIG. 7 is a rear elevational view thereof; and,

FIG. 8 is a reference view showing the coaxial cable connector in use.
The broken lines depict unclaimed portions of the connector, and thus form no part of the claimed design.

1 Claim, 8 Drawing Sheets
